DENTAL GINGIVAL PACKING TOOL

Robert Philip Berger, 17110 Clemons Drive,
Encino, Calif. 91316

Filed Dec. 29, 1969, Ser. No. 20,653

Term of patent 14 years

The term of this patent subsequent to Jan. 4, 1986,
has been disclaimed

Int. Cl. D24—02

U.S. Cl. D24—1 D

FIG. 1 is a perspective view of a dental gingival packing tool, showing my new design;

FIG. 2 is a side elevation thereof;

FIG. 3 is a top plan view thereof;

FIG. 4 is an end elevation thereof; and

FIG. 5 is an enlarged fragmentary view of the gripping surface of the dental gingival packing tool.

I claim:

The ornamental design of a dental gingival packing tool, substantially as shown.
